UNITED STATES PATENT OFFICE

GEORGE H. CUSHING, OF WASHINGTON, DISTRICT OF COLUMBIA, ASSIGNOR TO CUSHING LAMP INCORPORATED, OF WASHINGTON, DISTRICT OF COLUMBIA, A CORPORATION OF DELAWARE

FOCUSING MECHANISM

Application filed February 16, 1929. Serial No. 340,570.

This invention relates generally to illumination and more particularly has reference to a mechanism for adjusting the position of a light source relative to the reflector of a projecting lamp, and to means for retaining the light source in adjusted positions.

Projecting lamps that are scientifically constructed are designed upon a predetermined relation between the light source and the reflecting surfaces. It has been found, however, that the position of a filament in the electric lamps available on the market may vary sufficiently to disturb the characteristics of a projecting lamp designed for a particular relation between the filament and the reflector.

An object of this invention is to devise a mechanism for moving a light source relative to a reflector of a projecting lamp to secure a desired relation between the light source and a reflector.

Another object of this invention is to provide a mechanism by means of which a light source may be adjusted to various positions relative to a reflector and which is provided with a means for locking the light source in any adjusted position.

Another object of this invention is to provide a mechanism for mounting a light source within a projecting lamp in such a manner that the light source may be finally adjusted to various positions.

Another object of this invention is to devise a mechanism for mounting a light source in a projecting lamp in such a manner that the light source may be adjusted to various positions without being rotated.

Still another object of this invention is to devise a mechanism for supporting a light source within a projecting lamp in such a manner that it may be accurately adjusted to various positions relative to a reflecting surface, and which is capable of being easily attached to the light supporting means of a projecting lamp.

With these and other objects in view which may be incident to my improvements, the invention consists in the parts and combinations to be hereinafter set forth and claimed, with the understanding that the several neces-

sary elements comprising my invention may be varied in construction, proportions, and arrangement without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation have been made the subject of illustration.

In the drawings:

Figure 1 is a side view of the mechanism for adjustably supporting an electric lamp relative to a reflecting surface.

Figure 2 is a view showing the lamp carrying mechanism mounted in operative position within a projecting lamp.

Figure 3 is a view similar to Figure 1 with parts of the mechanism removed in order to show the details of construction of the slotted supporting member.

Figure 4 is a sectional view of the nut adapted to cooperate with the slotted portion of the supporting member shown in Figure 3.

Figure 5 is a sectional view of the nut adapted to be threaded onto the supporting member shown in Figure 3 to securely connect the supporting portion to the housing of the projecting lamp.

Figure 6 is a view showing a lamp socket threadedly mounted within the bushing which cooperates with the supporting member to move the lamp socket to various positions.

Figure 7 is a sectional view through the supporting member with all other parts removed.

Figure 8 is a sectional view of the exteriorly and interiorly threaded bushing.

Figure 9 is a view of the threaded lamp socket.

Figure 10 is an end view of the supporting member shown in Figure 7 looking at the tapered end.

Figure 11 is an end view of the supporting member taken from the other end thereof.

Figure 12 is a sectional view of the device

shown in Figure 1 showing the details of construction.

Figure 13 is a partial sectional view of the focusing device showing the details of construction of the spring-operated shoe.

Figure 14 is a view showing the shoe and its supporting member.

Referring to the drawings, in Figure 1 my device is shown mounted on a wall or support 1 represented by the dotted line construction. This wall or support 1 may constitute a portion of any structure to which the device supporting the adjustable light source 2 may be applied. In some instances, however, it will be desirable to mount the mechanism for supporting and adjusting a light source on the housing of a projecting lamp so that the light source may be adjusted axially of a reflector of the parabolic or other similar type.

As shown in Figure 2 the tubular structure for supporting the adjustable light source 2 is secured to the support 3 in the projecting lamp in such a manner that the light source 2 and its protecting bulb 4 may be moved axially of the structure 3.

The device which is adapted to be secured to a lamp housing or other supporting member, for adjustably holding the light source 2 and its protecting bulb 4 includes among other parts a combined support and clutch 6. Referring more particularly to Figures 1, 3, 7 and 12, it will be seen that this member 6 comprises a tubular structure having a body portion 7 from one end of which extends an annularly projecting flange 8. Screw threads 9 are provided on the body portion 7 onto which is threaded a nut 10 which is shown in detail in Figure 5. In mounting the member 6 on a supporting wall, an aperture is provided in the wall into which the tubular member 6 is inserted. When in place, the flange 8 engages one side of the wall and the nut 10 is threaded onto the screw threads 9 in such a manner that it engages the wall and securely holds it between the nut 10 and the flange 8.

Extending from the body portion of the tubular member 6 is a reduced portion 11, the end of which tapers to a smaller diameter 50 and thereby forming a tapered surface 12, the purpose of which will appear hereinafter. The reduced portion 11, as shown clearly in Figures 3, 7 and 10 is provided with a plurality of slots 13 which impart resiliency to it. 55 A plurality of screw threads 14 are provided within the reduced portion 11 of the supporting member, into which is threaded an exteriorly and interiorly threaded bushing or sleeve 15. As shown in the drawings the exterior threads 16 are of a pitch and hand corresponding to the pitch and hand of the threads 14, whereas the interior threads 17 are of a pitch greater than the threads 16 and are of an opposite hand.

65 For purposes of illustration, the threads 16

have been shown as right handed, while threads 17 have been shown as left handed. I wish it to be understood, however, that either set of threads may be of either hand and also the pitch of either set of threads 16 or 17 may be greater than the other or equal to each other, depending upon the particular results desired. In order to rotate the bushing 15 one portion thereof is knurled, as at 18, or otherwise constructed, so that it can be gripped with one's fingers.

Slidably mounted in the tubular member 6 is a sleeve 19 which serves as a socket for receiving the base 20 of the bulb 4. This member is provided with bayonet slots 21 at each end, one set of which is adapted to receive pins projecting from the base of an electric bulb and the other set of which is provided for the reception of pins projecting from a connecting plug 22. As shown in Figure 12, a member 23, formed of insulating material and having resiliently mounted current conductors 24 embedded therein, is positioned in the sleeve or socket 19 and serves to conduct current from plug 22 to the light source. It is, of course, obvious that any other construction suitable for connecting a light source to a source of electric energy may be employed.

50 Sleeve 19 is provided with exterior threads 25 which are of the same pitch and hand as threads 17 of bushing 15. As shown in the drawings, threads 25 are left handed, but I wish it to be understood that they may be right handed provided the other threads are changed accordingly to produce the desired result.

With the bushing 15 mounted in the tubular member 6 and the socket forming sleeve 19, entheaded within the bushing 15, it will be clear that if the member 6 and the sleeve 19 are held against rotation and the bushing 15 rotated, the sleeve 19 will, by reason of the differential thread construction move relatively to the tubular member 6. Thus with the member 6 secured to a fixed support, such as shown in Figure 2, a bulb carried by the sleeve 19 will be moved axially of the reflector upon rotation of the bushing 15.

In order to prevent the sleeve or socket 115 from rotating upon rotation of the bushing 15, the sleeve is provided with a slot 26, formed in the walls thereof between the bayonet slots 21. Projecting into the slot 26 is a shoe 27 carried by a spring pressed plunger 28 having a diameter larger than the width of the slot 26, the purpose of which will appear hereinafter. The plunger is mounted in an aperture provided in the flange 8, together with a suitable spring 29 and a plug 30 for holding the spring in engagement with the plunger.

As before mentioned, and as clearly shown in Figure 13, the plunger is of a diameter greater than the width of slot 26 so that it will not be forced out of place when the base 120

of a bulb is removed from the socket 19. It will be noted that a portion of the plunger is reduced in size so that the shoe will project slightly into the socket 19. This construction 5 permits the action of the spring 29 to be transmitted through shoe 27 to the side of the base of a bulb mounted in the socket, so that the bulb will be frictionally held against accidental displacement. To prevent the shoe interfering with the insertion of a lamp in the 10 socket a portion of the shoe is rounded off as shown at 31 in Figure 14. If desired the other end of the shoe 27 may be rounded similar to the portion 31. While it is desirable 15 to utilize the shoe construction just described, for preventing rotation of the sleeve 19 in the member 6, other constructions may be used such as an ordinary projecting lug mounted on member 6.

20 The slot construction just described also serves to prevent the light source from rotating. It is important that the light source does not rotate as the efficiency of the projecting device depends to a certain extent on 25 the position of the filament of the light source. When the projecting structure is designed for one position of the filament, it is essential that the latter be maintained in that position.

Once an adjustment is made on the device 30 just described it may be maintained by a novel clutch arrangement. As previously described, the reduced portion 11 of member 6 is provided with slots 13 to divide the reduced portion into a plurality of jaws. The external 35 surface of this reduced portion is also provided with a tapered surface 12. A suitable clutch clamping nut 32, shown in detail in Figure 4, is provided with internal threads 33 adapted to engage with threads 9 on tubular member 6 and with a tapered portion 34 adapted to engage with the tapered surface 12. As the clamping nut 32 is threaded onto the threads 9 the tapered portion 34 engages with the tapered surface 12 and causes the 40 jaws formed from the reduced surface of the member 6 to tightly clamp the externally threaded portion of the bushing 15. When the clamping nut 32 is in operative position, the bushing 15 will be held against rotation 45 and the sleeve 19 will be securely held in an adjusted position. The type of locking device just described has a tendency to automatically lock itself. For instance, when subjected to vibrations instead of becoming loose, 50 the nut 32, due to the taper construction, becomes more secure on the member on which it is mounted.

It will be noted from the drawings that the 55 end of member 6 adjacent flange 8 is provided with a lip 35 which may serve as a support for a reflector with which the device is associated.

In some instances it will be desirable to 60 have the bulb of such a size that it may be drawn within the tubular member 6. This

may be accomplished either by making the focusing construction large enough to receive a standard bulb or by using bulbs of a diameter sufficiently small to enter into the member 6. I wish it to be clearly understood that 70 while an elongated bulb has been shown by way of illustration that the device will operate equally well with spherical or other types of bulbs.

In operation the several parts of the mechanism just described are assembled as clearly shown in Figure 12. The structure is then secured to a supporting wall or to the housing of a projection lamp by means of the nut 10 and the annular flange 8. After a bulb 75 has been inserted in a socket provided by sleeve 19, the sleeve may be moved as desired, by rotating the bushing 15 in the proper direction. It will be appreciated that by constructing the threads 16 and 17 of opposite hand and rotating the bushing 15 through one revolution that the bushing will move into the member 6 a distance equal to the pitch of threads 16 and that the sleeve 19 will move through bushing 15 a distance 80 equal to the pitch of threads 17. Thus upon one revolution of the bushing 15 the sleeve 19 will move relatively to the member 6 a distance equal to the sum of the pitches of threads 16 and 17.

When the sleeve 19 carrying the bulb is 85 adjusted to the desired position, the clamping nut 32 may be tightened so that the jaws of the clutch, formed by slotting the reduced portion 11 of member 6, will tightly engage the external threaded surface of bushing 15 and prevent any rotation thereof.

It will be observed from the foregoing description that this invention provides a construction by means of which the light source 95 may be moved to any desired position axially of a reflector so that the best results can be obtained. It will also be appreciated that my device provides a means for locking the light source after it is once adjusted so that it will 100 not be accidentally displaced.

While I have shown and described the preferred embodiment of my invention, I wish 105 it to be understood that I do not confine myself to the precise details of construction herein set forth, by way of illustration, as it is apparent that may changes and variations 110 may be made therein, by those skilled in the art, without departing from the spirit of the invention, or exceeding the scope of the appended claims.

I claim:

1. A device for adjusting the position of a filament of an electric light bulb relatively to a reflecting surface, comprising a tubular member mounted in fixed relation to a reflecting surface, a sleeve adapted to receive the base of an electric light bulb slidably mounted in said member, an internally and externally threaded bushing positioned between 125

said sleeve and member, the external threads being of one hand and engaging with threads in said member, the internal threads being of another hand and engaging with threads on said sleeve, said bushing upon rotation being adapted to move the sleeve relatively to said member, and tightening means carried by said member for locking the sleeve in adjusted positions.

10 2. A focusing mechanism for a projecting lamp, comprising a tubular member having a body portion and a reduced portion, an annular flange extending from the body portion of the tubular member, a nut adapted to be threaded on said portion to cooperate with said flange for securing said member to a supporting wall, the reduced portion of said member being slotted to provide a plurality of jaws, supporting means for a light source 20 slidably mounted in said tubular member, means for adjusting the position of said supporting means, a clamping nut threaded on said tubular member and adapted to force said jaws into frictional engagement with said supporting means to prevent movement thereof.

3. A device of the character described comprising a lamp socket, means threadedly engaging said socket for moving it axially, said 30 socket having a slot cut axially adjacent one end and means adapted to cooperate with said slot for preventing rotation of said socket, said last mentioned means comprising a spring pressed shoe adapted to frictionally engage with the base of a lamp mounted in said socket.

4. In combination with a projecting reflector a device for holding a lamp at the focus of said reflector comprising a supporting member, a lamp socket having external threads and means for moving said socket relative to said supporting member, said member having an annular projection internally threaded, a bushing externally threaded and mounted within said projection, said bushing also being internally threaded and adapted to cooperate with the threads of said socket, said threads being so constructed that when said bushing is rotated relatively 50 to said member said socket will move axially relatively to said bushing and said member.

5. An adjustable lamp holder comprising an annular supporting member internally threaded, a lamp socket having external 55 threads, a bushing externally threaded and positioned in said member, said bushing also being internally threaded to receive the externally threaded lamp socket, the threads between said member and said bushing being of one hand and the threads between said bushing and said socket being of the other hand, and the pitch of the threads between said 60 socket and said bushing being greater than the pitch of the threads between said bushing and said member.

6. An adjustable lamp holder comprising an annular supporting member internally threaded, a lamp socket having external threads, a bushing externally threaded and positioned in said member, said bushing also being internally threaded to receive the externally threaded lamp socket, the pitch of the threads between said bushing and supporting member being less than the pitch of the threads between said bushing and said socket.

7. An adjustable lamp holder comprising an annular supporting member internally threaded, a lamp socket having external threads, a bushing externally threaded and positioned in said member, said bushing also being internally threaded to receive the externally threaded lamp socket, the threads between said member and said bushing being of one hand and the threads between said bushing and said socket being of the other hand.

In testimony whereof I affix my signature.
GEORGE H. CUSHING.
